UNITED STATES PATENT OFFICE

2,565,527

FEEDING MECHANISM FOR AUTOMATIC FIREARMS

Clarence E. Simpson, Springfield, Mass., assignor to the United States of America as represented by the Secretary of War

Original application June 7, 1946, Serial No. 675,124. Divided and this application February 24, 1948, Serial No. 10,549

7 Claims. (Cl. 89—33)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to a feeding mechanism for an automatic firearm of the recoiling barrel type.

This application is a division of my application for Automatic Firearms, Serial No. 675,124, filed June 7, 1946, now Patent No. 2,555,379.

It is an object of this invention to provide a feeding mechanism for an automatic firearm having a recoiling barrel and related breech members.

Another object of this invention is to provide a feeding mechanism for an automatic firearm utilizing ammunition contained in conveniently handled strips, such ammunition being aligned in the feedway by mechanical means independent of the recoiling members of the firearm.

The specific nature of the invention as well as other objects and advantages thereof will clearly appear from a description of a preferred embodiment as shown in the accompanying drawings in which:

Fig. 1 is a fragmentary top view of the firearm showing the cartridge strip positioned in the feedway.

Fig. 2 is a perspective view of the cartridge strip utilized for holding the ammunition.

Fig. 3 is a detail perspective view of the feedway.

Fig. 4 is a cross-sectional view taken along the line 4—4 of Fig. 1.

Fig. 5 is a right side view of the recoiling members of the firearm showing the position of the feedway with respect to such members.

Fig. 6 is a sectional view taken along the line 6—6 of Fig. 4.

Fig. 7 is a cross-sectional view taken along the line 7—7 of Fig. 4.

Fig. 8 is a fragmentary side view of the firearm showing the manner of supporting the front portion of the barrel.

Fig. 9 is an enlarged fragmentary left side view of the firearm showing the manner of securing the feedway to the receiver.

Fig. 10 is an enlarged detail perspective view of the feedway locking pin.

Fig. 11 is a fragmentary detail view of the lug shown in perspective utilized to receive the feedway locking pin.

Referring to Figs. 5 and 8 there is shown in assembled relation a firearm embodying this in-

2

vention. A receiver 10 is provided to support the recoiling elements of the firearm. Such receiver essentially comprises a pair of spaced parallel side plates 11 and 12. Near the upper edge of the side plates 11 and 12 there is provided a longitudinal groove-like guideway 13 to slidably support a barrel extension 14. A vertically disposed cutaway portion 15 at the forward end of guideway 13 permits easy removal of barrel extension 14. A tube 16 secured to the forward end of receiver 10 is horizontally disposed and contains a hydraulic recoil and counter-recoil mechanism which is fully described in my U. S. Patent No. 2,364,103. A front barrel bearing support 17 is provided to support the forward end of a barrel 18. The breech end of such barrel is preferably threadably secured to barrel extension 14. The front barrel bearing support 17 is so constructed as to permit limited vertical movement of barrel 18 when removing barrel extension 14 and barrel 18 from receiver 10 for disassembly purposes as fully shown and described in my application for Automatic Firearm, Serial No. 675,124, filed June 7, 1946.

A breech block 19 and breech block carriage 20 are slidably mounted in receiver 10. Breech block 19 in turn is slidably mounted on carrier 20 and is arranged to be locked to barrel extension 14 by suitable locking lugs (not shown). On the recoil stroke of the firearm, barrel 18, barrel extension 14, breech block 19 and breech block carrier 20 recoil to the end of the recoil stroke as a unit. At the completion of such stroke, barrel 18 and barrel extension 14 are returned to battery position by means of the hydraulic mechanism contained in tube 16. As soon as such members reach battery position, breech block 19, which has been separated from breech block carrier 20, is then forced to battery position and is raised into locked relationship with barrel extension 14 as shown in Fig. 5.

The above briefly describes the functioning of the main elements of the firearm embodying the preferred form of this invention and should suffice to illustrate the workings thereof. A more detailed description may be had by reference to my copending application Serial No. 675,124, filed June 7, 1946 for Firearm.

50 A feedway 21 is transversely mounted on top of side plates 11 and 12 and substantially comprises a horizontal shelf 22 (Figs. 3 and 4). A large substantially rectangular depending portion 23 is provided on the underside of shelf portion 22 which is bifurcated by a semi-circular cut 24 to

permit the feedway 21 to be lowered over barrel 18 as will be presently described. A rectangular recess 25 is provided in the rectangular depending portion 23 (Fig. 4) to permit barrel extension 14 to slide forwardly underneath shelf 22 a short distance. Two oppositely disposed lugs 26 and 27 are formed by the semi-circular cut 24 each of which is bifurcated as shown at 28 (Fig. 6) and a longitudinal hole 29 is provided in each of the lugs 26 and 27. A broad T-slot 30 (Figs. 3, 6 and 7) parallel to the longitudinal sides of shelf portion 22 is provided on the top of such shelf portion to receive a cartridge strip 31 to be presently described. A raised rib 32 is centrally provided on the bottom of T-slot 30 for a purpose to be described. An integral substantially cylindrical housing 33 is provided on the left side of feedway 21 as shown in Figs. 3 and 4. The cylindrical housing 33 contains a spring-like tape 34 for actuating the cartridge strip 31.

Feedway 21 is pivotally mounted on the right side of the firearm by a bracket (not shown) secured to side plate 12. The right hand lugs 27 of the feedway are utilized to mount the feedway to the bracket (not shown). A pin (not shown) pivotally secures such feedway to the bracket.

On side plate 11 there is mounted a bracket 35 as shown in Figs. 9 and 11. Bracket 35 is placed within a suitable vertical slot (not shown) in side plate 11 and is secured to such side plate as by screws. An upwardly projecting lug 36 is provided on the upper edge of bracket 35 and a longitudinal hole 37 is provided therein. A longitudinal slot 38 (Fig. 11) communicates with hole 37 to permit a feedway release pin 39 to enter therein as will be presently described.

When feedway 21 is pivoted into position over barrel 18, the bifurcated left hand lug 26 of the feedway engages lug 36 on bracket 35 thereby aligning hole 37 with holes 29 in lug 26 as shown in Fig. 9. Feedway release pin 39 comprises a pin 41 having an integral head 42. A flat milled section 43 is provided in the center of pin 41 of slightly lesser width than slot 38 on lug 36 of bracket 35. Thus pin 41 enters hole 29 through slot 38. When pin 41 is rotated counterclockwise, feedway 21 is locked to bracket 35. A suitable recess 44 is provided on the top of the rear edge of shelf portion 22 to accommodate a cartridge support 45 and to provide clearance for breech block 19.

A hole 47 disposed parallel to the axis of the firearm (Figs. 4 and 7) is provided in the portion 23 underneath shelf 22 in which is inserted a cartridge strip retaining plunger 46. The plunger 46 comprises a hollow tubular member having an integral upstanding head 48 at the forward end thereof. Head 48 rests within a suitable recess 49 in the left hand edge of T-slot 30. A helical spring 50 is placed within the hollow interior of plunger 46 and is retained therein by a cylindrical member 51, such member is in turn retained by a pin 52 inserted in a vertical hole 53 in the bottom of T-slot 30 and in turn passes through a slotted hole 54 in plunger 46 and through a suitable hole in cylindrical member 51. Limited longitudinal movement of plunger 46 is thus provided by the slotted hole 54. Spring 50 biases the headless end of plunger 46 into the rectangular recess 25 and head 48 into the path of the cartridge strip 31 as will be described. The end of plunger 46 projecting into recess 25 is struck by the forward face of barrel extension 14 for the purpose of pushing head 48 of plunger 46 out of the path of strip 31 to permit feeding another

round into the action of the firearm as will be later described.

The cartridge strip actuating tape 34 is wound about a spool 55 which is inserted within cylindrical housing 33. The spool 55 is provided with an integral flange 56 to retain tape 34 on such spool as shown in Fig. 6. A spindle 57 is provided for mounting spool 55. Such spindle has an integral head 58 which is rotatably supported by the rear wall of cylindrical housing 33. Adjacent spool 55 a squared portion 59 is provided on spindle 57 and upon such squared portion a hub 60 is placed. A spring retainer 61 of the same diameter as spool 55 is inserted within housing 33 and likewise placed adjacent spool 55. Two integral outwardly facing oppositely disposed lugs 62 are provided on retainer 61. One end of a flat clock-type spring 63 is secured to hub 60 in suitable fashion while the other end of spring 63 is secured to retainer 61 as by a rivet. Spring 63 is arranged to be wound by a disk-like cover 64. An integral knob 65 having a knurled outer surface is centrally provided on cover 64 to facilitate turning such cover and winding spring 63 as will be presently described.

An axial cylindrical recess 66 is provided on the inside surface of cover 64 to support the forward end of spindle 57. Two oppositely disposed arcuate solets 67 are provided on the underside of cover 64 which are engaged by the lugs 62. One end of tape 34 is secured to spool 55 by passing that end of such tape about a pin 68 and inserting the tape and such pin in a transverse slotted hole 69 in spool 55 as shown in Fig. 4. The tape 34 is then wound about spool 55, while the free end of tape 34 is passed along the bottom of a longitudinal T-slot 70 provided in rib 32 of feedway 21 where it connects with a strip actuating slide 71 adapted to cooperate with T-slot 70. The other end of tape 34 is secured to slide 71 in the same manner as to spool 55. A slot 72 is provided in slide 71 as shown in Fig. 4 which engages the end of cartridge strip 31 as will be presently described.

The cover 64 is restrained against turning by a locking spring 73 (Fig. 1) which comprises a rod-like member having one end of reduced thickness. On the underside of such spring there is provided an integral projection 74 which engages a slot 75 on the top surface of knob 65. The rod-like portion of spring 73 is inserted in a hole 76 is feedway 21 as shown in Fig. 9. The projecting end of spring 73 is turned upwardly for convenience in grasping as shown in Fig. 1. To place clock-type spring 63 under tension, spring 73 is raised to disengage projection 74 from slot 75. Knob 65 may then be turned in a counterclockwise direction until spring 63 is under the tension desired. When spring 63 is placed under tension, such force is transmitted to spool 55 and in turn to tape 34 for actuating cartridge strip 31 as will be presently described.

The cartridge strip or cartridge feed member 31 comprises a shallow, channel-shaped member having outwardly flared sides 77 which rest within T-slot 30 as shown in Fig. 1. A plurality of cartridge clips 78 comprising substantially semi-cylindrical tubes are secured to the top surface of strip 31 as by rivets 79. The clips 78 are tapered as shown in Figs. 1 and 2 to conform to the taper of a cartridge case 80. The sides of clips 78 engage somewhat more than half the periphery of each cartridge 80 as shown most clearly in Fig. 4 to securely, yet yieldingly, hold such cartridge case. An integral spring posi-

tioning detent 81 is provided on the rear end of each clip which is suitably formed to fit within an extractor groove 82 provided at the rear end of each cartridge 80 and strike the inside of the rim of each case 80 to align the bases of the cartridges in strip 31.

A plurality of wedge-shaped notches 83 (Figs. 1 and 2) are provided on the forward edge of each strip 31. The notches 83 have the same spacing as cartridge clips 78 and are provided to be engaged by the head 48 of cartridge strip retaining plunger 46. The cartridge strip 31 is inserted into the feedway from the left side of the firearm as shown in Fig. 1, the flared sides 77 engaging T-slot 30. The right end of cartridge strip 31 then engages a slot 72 of slide 71 thereby unreeling tape 34 from spool 55. Thus tape 34 biases strip 31 to the left to bring each cartridge 80 into feeding position. A cartridge stop pawl 84 is pivotally mounted in the upper left hand corner of feedway 21 as shown in Fig. 1 to arrest and to align each cartridge in the feedway and such pawl is pivotally mounted on a pin 85. A spring 86 is inserted within a suitable slot to bias one end of pawl 84 upwardly into the path of a cartridge 80.

Upon firing a cartridge the barrel 18, barrel extension 14, breech block 19, and breech block carrier 20 recoil as a unit until the breech block carrier 20 strikes a buffer mechanism (not shown) at the rear of the firearm. As barrel 18 and barrel extension 14 recoil rearwardly, the cartridge strip retaining plunger 46 is biased rearwardly by spring 50. The head of such plunger engages one of the notches 83 on strip 31 to secure such strip against lateral movement.

On the counter-recoil stroke, barrel extension 14 and barrel 12 continue forwardly thereby forcing breech block 19 to slide downwardly on the inclined surface of breech block carrier 20 whereupon such block becomes disengaged from barrel extension 14 and such extension moves forwardly into battery position. Upon going into battery position, barrel extension 14 strikes the cartridge strip retaining plunger 46 shown in Figs. 1 and 7 and forces head 48 out of engagement with notch 83 in strip 31 permitting such strip to move to the left as shown in Fig. 1 until the next round in the strip contacts stop pawl 84 which horizontally aligns the next cartridge in feedway 21 where it can again be engaged by breech block 19 as such breech block comes forwardly to the breeched position shown in Fig. 1. Upon extracting the last round from cartridge strip 31 slide 34 forcibly ejects strip 31 out of feedway 21 leaving such feedway clear for quick insertion of a fully loaded strip.

From the foregoing description it is clearly apparent to those skilled in the art that there is here provided a cartridge feeding mechanism for an automatic firearm that is of unique and simple construction and one that will positively advance the cartridges into position to be extracted from the cartridge retaining strip to permit feeding of such cartridge into the barrel of a firearm.

I claim:

1. In a firearm having a recoiling member reciprocable from and to a battery position, a feedway disposed transversely relative to the path of said recoiling member, a cartridge feed member slidably insertable in said feedway, said feed member being provided with a plurality of clips and adapted to support a row of cartridges, resilient means for biasing said feed member

transversely along said feedway in a direction counter to the direction of insertion of said feed member in said feedway, a stop member adapted to engage the foremost cartridge of the row in the counter-insertion direction to position said feed member in said feedway against the bias of said resilient means, and means on said recoil member for successively withdrawing the foremost cartridge from the row with each reciprocation of said recoil member whereby said feed member is ejected from said feedway following withdrawal of the last cartridge from the row.

2. In a firearm having a recoil member reciprocable from and to a battery position, a feedway disposed transversely relative to the path of said recoil member and adapted to receive a strip of linked cartridges therein, means for biasing the strip of cartridges along the feedway in a feeding direction, and means responsive to the movement of said recoil member out of its said battery position for preventing feeding movement of the strip of cartridges.

3. In a firearm having a recoil member reciprocable from and to a battery position, a feedway disposed transversely relative to the path of said recoil member, a cartridge feed member mounted for intermittent movement along said feedway, said feed member being adapted to support a row of cartridges, resilient means for biasing said feed member in a feeding direction along said feedway, a stop member adapted to engage the foremost cartridge of the row to limit feeding movement of said feed member, means on said recoil member for successively withdrawing the foremost cartridge from the row with each reciprocation of said recoil member, and means responsive to the movement of said recoil member out of its said battery position for preventing feeding movement of said feed member.

4. In a firearm having a recoil member reciprocable from and to a battery position, a unitary member defining a feedway, means for pivotally securing said member to said firearm, said feedway being disposed transversely relative to the path of said recoil member and adapted to receive a strip of linked cartridges therein, resilient means for biasing the strip of cartridges along said feedway in a feeding direction, and means responsive to the movement of said recoil member out of its said battery position for preventing feeding movement of the strip of cartridges.

5. In a firearm having a recoil member reciprocable from and to a battery position, a unitary member defining a feedway, means for pivotally securing said member to said firearm, said feedway being disposed transversely relative to the path of said recoil member and adapted to receive a strip of linked cartridges therein, resilient means for biasing the strip of cartridges transversely along said feedway in a feeding direction, a stop member adapted to engage the foremost cartridge of the row in the counter-insertion direction to position said feed member in said feedway against the bias of said resilient means, and means on said recoil member for successively withdrawing the foremost cartridge from the row with each reciprocation of said recoil member.

6. In a firearm having a recoil member reciprocable from and to a battery position, a feedway disposed transversely relative to the path of said recoil member, a cartridge feed member slidably insertable in said feedway, said

feed member being adapted to support a row of cartridges, a spindle rotatably mounted on the firearm, a flexible tape member having one end engageable by said feed member and the other end secured to said spindle, resilient means for imparting a rotational bias to said spindle thereby biasing said feed member transversely along said feedway in a direction counter to the direction of insertion of said feed member in said feedway, a stop member adapted to engage the foremost cartridge of the row in the counter-insertion direction to position said feed member in said feedway against the bias of said resilient means, and means on said recoiling member for successively withdrawing the foremost cartridge from the row with each reciprocation of said recoiling member whereby said feed member is ejected from said feedway following withdrawal of the last cartridge from the row.

7. In a firearm having a recoiling member reciprocable from and to a battery position, a unitary member defining a feedway, means for pivotally securing said member to said firearm, said feedway being disposed transversely relative to the path of said recoiling member and adapted to receive a strip of linked cartridges

therein, resilient means for biasing the strip of cartridges along said feedway in a feeding direction, and means responsive to the movement of said recoiling member out of its said battery position for preventing feeding movement of the strip of cartridges, said resilient means comprising a spindle rotatably mounted on the firearm, a flexible tape member having one end engageable by said feedway member and the other end secured to said spindle, and resilient means for imparting a rotational bias to said spindle.
